(57) **CLAIM**

The ornamental design for a surface configuration of the front and rear portions of a vehicle, toy, and/or other replicas, as shown and described.

DESCRIPTION

This application is related to the following co-pending applications, of the inventor, filed on even date herewith: Application Ser. No. 29/222,969, entitled "Surface Configuration of a Front Bumper for a Vehicle"; and Application Ser. No. 29/222,970, entitled "Surface Configuration of a Vehicle Spoiler".

FIG. 1 is a right, front perspective view of a surface configuration of the front and rear portions of a vehicle, toy, and/or other replicas according to our novel design;

FIG. 2 is a front view of the surface configuration of the front and rear portions of a vehicle, toy, and/or other replicas according to our novel design;

FIG. 3 is a left, rear perspective view of the surface configuration of the front and rear portions of a vehicle, toy, and/or other replicas according to our novel design;

FIG. 4 is a left side view of the surface configuration of the front and rear portions of a vehicle, toy, and/or other replicas according to our novel design, the right side view being mirror symmetrical; and,

FIG. 5 is a rear view of the surface configuration of the front and rear portions of a vehicle, toy, and/or other replicas according to our novel design.

The broken lines are for illustrative purposes only and form no part of the claimed design.
